Primary Examiner—Alan P. Douglas*Assistant Examiner*—S. Snapp*Attorney, Agent, or Firm*—Francis X. LoJacono[57] **CLAIM**

The ornamental design for a remote control holder for electronic equipment, as shown and described.

DESCRIPTION

FIG. 1 is a front-perspective view of a remote control holder for electronic equipment, showing my new design. The remote controls are shown in phantom lines and are not part of the claimed design;

FIG. 2 is a top plan view thereof;

FIG. 3 is a front elevational view thereof;

FIG. 4 is a right side-elevational view not seen in FIG. 1;

FIG. 5 is a rear-elevational view thereof; and,

FIG. 6 is a bottom plan view thereof.
